RHEOSTAT

Frank G. Logan, Mount Vernon, N. Y., assignor to
 Ward Leonard Electric Company, a corporation
 of New York

Original application January 18, 1939, Serial No.
 251,468. Divided and this application Decem-
 ber 9, 1939, Serial No. 308,341

8 Claims. (Cl. 201—55)

This invention relates to improved means for variably controlling the amount of resistance in a circuit and is capable of application to many different forms of controlling apparatus. It is particularly useful where a wide change of the controlling resistance is desirable by a comparatively small movement of the movable element. It likewise is particularly advantageous where refinement of control is desirable by providing a graduated control of a multiplicity of contacts with comparatively small movement of the movable element. The invention also relates to means for actuating and controlling the movable element in a simple manner and by refined adjustments.

This application is a division of my pending application Serial No. 251,468, filed January 18, 1939.

The main objects of the invention are to provide a simple and inexpensive form of construction which will be dependable in operation, rugged and compact in structure, not easily affected by tilt or shock and adapted to withstand severe service with a minimum amount of attention. Another object is to provide means whereby the resistance may be adjusted within comparatively close limits and wherein a pronounced change of resistance may be quickly obtained by a comparatively small movement of the movable element. Another object is to provide a structure in which the movable parts will have comparatively a small mass and inertia. Another object is to provide a wiping contact between the movable element and the resistance contacts and a proper amount of contact pressure which will avoid objectionable wear of the parts while maintaining the contacts clean and insuring good contact and long life without sparking. Another object is to provide a form of relative movement between the resistance contacts and the movable element which will be along the contacts instead of across them which reduces the friction and wear of the parts and heightens the smoothness of control. Other objects and advantages of the invention will be understood from the following description and accompanying drawings showing preferred embodiments of the invention.

Fig. 1 is a front elevation of the controlling device and adjustable resistance of the regulator; Fig. 2 is a side view partly in section; Figs. 3, 4 and 5 are front plan and side views showing a different form of resistance unit; Fig. 6 is a front view of the movable contact and resistance element showing a different form; and Figs. 7

and 8 are similar views showing a form of resistance and contacts adapted for heavy duty.

Referring to Figs. 1 and 2, the parts are enclosed by and mounted on the back of a casing 1. The regulating resistance element 2 is in the form of a tube extending horizontally across the top portion of the casing. It is composed of a tube 2a of insulating refractory material, such as porcelain, on which are wound many turns of the resistive conductor 2b connected to terminals 2c at the ends of the tube. The resistive conductor and terminals, except where exposed for connection to an external circuit, are covered with a coating 2d of insulating material, such as vitreous enamel. The tube is supported at the end by sheet metal brackets 3 which in turn are fastened to the back of the casing. The tube, as shown in Fig. 2, is wedge-shaped to form a forwardly projecting edge. After enameling, the enamel covering the front edge is ground off so as to expose a portion of each turn of the resistive conductor at the front edge of the tube. This provides a smooth contacting surface for engagement by the movable element. The exposure of a portion of each adjoining turn of the resistive conductor provides a large number of steps for refined adjustment of the amount of resistance inserted in the control circuit. The tube may be wound with a resistive conductor of small size at the middle portion and of larger sizes as the outer ends of the tube are approached, as indicated in Fig. 1, in order to secure greater change in resistance between the turns of the central portion than between turns of the outer portion for the purpose of securing desired quantitative control.

Below the resistance unit is mounted the controlling electro-magnet or solenoid having a vertical coil 4 with supporting brackets 5 of sheet metal at the upper and lower ends which are in turn secured to the back of the casing 1. The solenoid coil is wound upon a brass tube 6 to which the brackets 5 are fixed. The tube projects above and below the controlling coil and serves to guide the movable element of the electromagnet or plunger 7 of magnetic material. The tube is slotted throughout its length in a vertical direction, as shown at 6a, for the purpose of reducing eddy currents; and the supporting brackets 5 are likewise slotted as shown at 5a for the same purpose.

The movable element 8 which contacts with the exposed front edge of the resistance unit is in the form of a metal strip, the inner edge

of which contacts with the exposed portions of the turns of the resistance unit. It is of a widely open V form with the ends 8a extending upward vertically. It is preferably made of silver, or alloy of silver for insuring good contact with the turns of the resistive conductor but may, if desired, be made of a base metal with the contacting portion of silver or of silver alloy. At the central apex of the contacting element 8 are secured brackets 9 which engage the opposite sides of a connecting strip 10 of insulating material. This strip extends downwardly into the coil 4 and is pivotally connected to the upper end of the plunger 7. The plunger 7 may be slotted longitudinally from the center outwardly as shown at 7a for reducing the induction of eddy currents.

The proper contact pressure of the movable element 8 against the contact edge of the resistive tube is imposed by a spring 11 secured at one end to the upper part of the strip 10 and at the other end to the end of a screw 12 which is fixed to and projects forwardly from the back of the casing. This insures that an equal pressure will be imposed on each leg of the V against the contacts and likewise insures that the contact pressure will be substantially uniform in all positions of the parts. A spring 13 is secured to the lower end of the plunger 7 and to a sheet metal plate 14 which is fixed to the back of the casing. This spring exerts a downward pull upon the plunger 7 and supplements the force of gravity tending to hold the same in its lowest position. At the lower end of the plunger is secured a small plate 15 which projects towards the back of the casing into a cutaway portion 14a of the plate 14. The plate thus serves as a stop for the plunger in its lowest and highest positions.

When the plunger is in its lowest position as shown in Figs. 1 and 2, the outer ends of the contacting element 8 are in engagement with the exposed portions of the terminal bands 2c and thereby short circuits all of the resistance of the tube 2. When the current in the coil 4 is increased, the plunger 7 is raised against gravity and the pull of the spring 13 and this action gradually reduces the short circuited portion of the resistive conductor; and when the plunger is in its highest position with the plate 15 against the upper stop, the middle of the element 8 is in engagement with the middle of the resistive conductor, at which time almost none of the resistance is short circuited by the element 8 and it is practically all inserted in the circuit to which the resistive conductor is connected. By this form of construction the distance of travel of the plunger and contacting element 8 is comparatively short by reason of the wide open V form of the movable element. This small range of movement from the resistance-all-out position to the resistance-all-in position insures a pronounced change of resistance with a comparatively small movement of the plunger and consequently imposes an adequate corrective change of resistance upon comparatively small change of current in the solenoid coil. Also, the multiplicity of contacts of the exposed portion of the resistive conductor secures refined control of the resistance upon any movement of the contacting element. The direction of movement of the element 8 over the exposed surface of the resistive conductor is always in the direction of the turns of the resistive conductor and not across them, securing a wiping contact with a minimum of frictional wear, while the spring 11 insures adequate and uniform con-

tact pressure in all positions of the controlling element. Furthermore, the weight of the movable parts is comparatively light permitting quick response of movement to any change of current and the low inertia likewise permits the movable portion of the system to quickly adjust itself to its correct position under any conditions of operation.

The form of construction may be changed to suit particular requirements and Figs. 3 to 8 show some of the modified forms which may be used for special purposes. Figs. 3 to 5 show a form of contact resistance element similar to that shown in Figs. 1 and 2 except that the resistive conductor is wound in the form of a flat plate 16 having a front contacting straight edge 16a where portions of the successive turns of the resistive conductor are exposed for engagement by the movable element 8. As shown in Fig. 4 the rearwardly extending portion of the plate may be made converging to permit the same size of resistive conductor to be used throughout its length, the shorter length of the turns at the ends securing a less change of resistance per turn near the end portion than is secured at the central portion of the plate.

Fig. 6 shows the shape of the parts reversed from that of Figs. 1 and 2. In Fig. 6 the movable contact element 17 is in the form of a straight strip or bar whereas the exposed contacting face 18 of the successive turns of the resistive conductor is of an inverted V-shape with widely diverging sides. Such a form of resistance element may be made by combining two flat plates meeting at the apex as shown in Fig. 6, or by similarly combining other forms of resistance units such as the tubular form of Figs. 1 and 2. Fig. 7 indicates a form particularly appropriate for use where the control of comparatively large current is necessary. Here there is a straight row of contacts 19 with resistive conductors 20 connected between successive contacts, the resistive wires being preferably covered with an insulating coating from which the contacts 19 project, as in the usual forms of plate rheostats. Fig. 8 is similar to Fig. 7 except that the movable contacting element 17 is in the form of a straight bar or strip, while the contacts 19 are arranged to form an inverted widely diverging V. It is evident that in each of these modifications the resistance is all short circuited when the movable contacting bar or strip is in its lowest position and is all inserted when in its upper position.

Instead of making the contacting bar or the contacts of wide open V formation, they could be arc shaped or of bow form or of any other equivalent form to secure the same results; and the description as of V form and the direction of the two legs of the V forming an obtuse angle between the legs in the claims is to be understood as covering such equivalents.

The invention is applicable to various uses and for various purposes, particularly where a large range of control and refined adjustment is desired to be accomplished by a comparatively short range of movement of the adjustable element. Various modifications may be made according to the conditions and particular requirements without departing from the scope of the invention.

I claim:

1. A rheostat comprising a resistive device having a plurality of contact surfaces adjoining each other in a row to form a contact member, an element contacting therewith to form a second contact member, one of said members extending

in an approximately straight line and the other of said members having a wide open V contact form and the direction of the two legs of the V forming an obtuse angle between the legs and contacting with the other member at each leg of the V, and means for moving one of said members relatively to the other in a direction perpendicular to said line and the contact engagement in the direction of relative movement being small.

2. A rheostat comprising a resistive device having a plurality of contact surfaces adjoining each other in a row to form a contact member, the contact surfaces thereof being in the form of a narrow projecting edge to have small contacting surfaces, an element contacting therewith to form a second contact member, one of said members extending in an approximately straight line and the other of said members having a wide open V contact form and the direction of the two legs of the V forming an obtuse angle between the legs and contacting with the other member at each leg of the V, and means for moving one of said members relatively to the other in a direction perpendicular to said line.

3. A rheostat comprising a support having turns of a resistive conductor thereon, said conductor having a narrow row of exposed contact surfaces adjoining each other to form a contact member, an element contacting therewith to form a second contact member, one of said members extending in an approximately straight line and the other of said members having a wide open V contact form and the direction of the two legs of the V forming an obtuse angle between the legs and contacting with the other member at each leg of the V, and means for moving one of said members relatively to the other in a direction perpendicular to said line.

4. A rheostat comprising a support having turns of a resistive conductor thereon, said conductor having a narrow row of exposed contact surfaces adjoining each other to form a contact member, an element contacting therewith to form a second contact member, one of said members extending in an approximately straight line and the other of said members having a wide open V contact form and the direction of the two legs of the V forming an obtuse angle between the legs and contacting with the other member at each leg of the V, and an electromagnet for moving one of said members relatively to the other in a direction perpendicular to said line.

5. A rheostat comprising a resistive device having a plurality of fixed contact surfaces ad-

joining each other in a row to form a contact member, a movable element contacting therewith to form a second contact member, one of said members extending in an approximately straight line and the other of said members having a wide open V contact form and the direction of the two legs of the V forming an obtuse angle between the legs and contacting with the other member at each leg of the V, and means for moving said movable element in a direction perpendicular to said line and the contact engagement in a direction of relative movement being small.

6. A rheostat comprising a resistive device having a fixed support and a plurality of conducting portions embracing said support and forming a narrow row of contact surfaces extending in an approximately straight line, a movable element having a wide open V contact form and the direction of the two legs of the V forming an obtuse angle between the legs and contacting with said row of surfaces at each leg of the V, and means for moving said element in a direction perpendicular to said line.

7. A rheostat comprising a resistive device having a plurality of fixed contact surfaces adjoining each other in a row to form a contact member, a movable element contacting therewith to form a second contact member, one of said members extending in an approximately straight line and the other of said members having a wide open V contact form and the direction of the two legs of the V forming an obtuse angle between the legs and contacting with the other member at each leg of the V, means for moving said movable element in a direction perpendicular to said line and the contact engagement in the direction of relative movement being small, and means for pressing said movable element against said fixed contacts with the same pressure at each leg of the V.

8. A rheostat comprising a resistive device having a plurality of fixed contact surfaces adjoining each other in a narrow row and extending in an approximately straight line, a movable element having a wide open V contact form and the direction of the two legs of the V forming an obtuse angle between the legs and contacting with said surfaces at each leg of the V, a solenoid for moving said element in a direction perpendicular to said line, and means for pressing said movable element against said contact surfaces with the same pressure at each leg of the V.

FRANK G. LOGAN.
